PARAFFIN SCRAPER

Marshall L. Claiborne, 200 W. Alto, Hobbs, N. Mex.
Filed Aug. 25, 1959, Ser. No. 835,976
3 Claims. (Cl. 166—170)

This invention pertains to oil wells and more particularly to a device for scraping paraffin from the inside of the production tube of a free flowing oil well.

This device is particularly designed and adapted to be used upon oil wells which have sufficient pressure to cause the oil to flow freely through a tube to the surface of the ground. A common problem with such type oil wells is the collection and accumulation of paraffin on the inside of the tubing.

This tool operates on the principle that the flow of the well may be stopped by closing a valve at the top of the well. Therefore any object in the tube which is heavier than the liquid in the tube will fall. On the other hand, if the valve at the top of the well is open, any object in the well will be carried upward with the flow of oil in the well.

An object of this invention is to provide such a free fall device which will effectively scrape the paraffin from the inside of the tube.

Another object is to provide such a tool which has little or no difficulty in freely falling when there is no flow of oil in the well yet which has good scraping action on both the downward and upward trip.

A further object of this invention is to provide a tool which is easy to catch and hold within the lubricator at the upper portion of the tube.

Still further objects are to achieve the above with a device that is sturdy, compact, durable, simple, and reliable, yet inexpensive and easy to manufacture.

The specific nature of the invention as well as other objects, uses, and advantages thereof will clearly appear from the following description and from the accompanying drawing, in which:

FIG. 1 is an elevational view of said tool in the tube.

FIG. 2 is a partial longitudinal section of the joint between the upper and lower section of the tool.

FIG. 3 is a partial longitudinal section of the joint between the lower section of the tool and the stop member.

As may be seen in the accompanying drawing, the tool is basically divided in two sections. As this general type of tool is well known, the lubricator and the catch in the bottom have not been shown.

The upper section 10 of the tool is basically a cylindrical body or member 12 which is closed at the top end. The top end is closed by shaft 14 for the easy engagement of fishing tools, generally called a fishing neck.

Around the exterior of the body 12 are two helical vanes 16. These vanes are welded or otherwise firmly secured to the body. The outside diameter of the tool with the vanes is only slightly smaller than the inside diameter of the tube within which the tool works.

Likewise lower section 18 has body 20 which is of cylindrical form. The body has two vanes 22 helically around it. As may be seen, both the bodies of the upper and lower section are made of tubular material. The top of the lower section body 20 has a plug 24. The outside diameter of the plug is the same as the inside diameter of the body so there is a snug fit. Holes may be bored in the side of the body 20 so that the plug is welded in place through the holes to the body 20. Pintle 26 rises coaxially with the tubular body 20. It is an integral part of the plug 24. The pintle extends through hole 28 of washer 30 which is attached to the lower end of the tubular upper body 12. Holes may be bored through the upper body 12 to weld the washer 30 in place. As may be seen, the washer has a substantial

2

thickness. The hole 28 is larger than the outside diameter of the pintle 26. Therefore there is a certain amount of play or possibility of vibration between the upper body and the lower body. A protuberance or stop or nut 32 is screwed onto threads at the top of the pintle and welded into place at the top of the pintle which is above the washer. As stated before, the whole connection is somewhat rough and permitting and encouraging vibration for reason which will be explained later.

10 Stop 34 is below the bottom section. The outside diameter of the stop is larger than the outside diameter of the tubular body 20 which is of the same diameter as the tubular body 12. However the diameter of the stop is less than the outside diameter of the entire tool 15 including vanes. Likewise extending vertically upward from the stop and coaxial with the tubular members is pintle 36 which extends through washer 38 which is attached to the lower body in the same manner as washer 30 is attached to the upper body. Likewise a nut or 20 protuberance 32 is at the top of pintle 36 and above washer 38 to connect the stop and lower body.

In operation the tool as a whole is dropped into the well when no oil is flowing upward. The tool is adapted not to hang easily because each of the sections will 25 tend to spiral as it goes down. If the tool hits some obstruction in the tube, the parts will spiral around as they go down. However, because the swivel between the lower member and the upper member is not machined to perfection, there will be a certain amount of friction 30 and vibration. This prevents perfect spiraling and accomplishes a great deal of paraffin removal. If only a single member is used which has a spiral in only one direction, it will tend to make a helical track down the inside of the tube and following this same track on repeated trips. If right and left handed veins are used on 35 a single member with no possible rotation between the two sections, there is no spiraling at all when the tool is traveling and more likely the tool will become stuck on paraffin deposits as it falls.

40 I have found it desirable to add a stop on the bottom which is mounted for rotation. When the tool strikes the catch which is mounted in the tube at the lower extreme of the tool's travel, there is no excessive rotation against the catch. Likewise when the tool is blown 45 upward and the tool is caught in the lubricator at the top of the tube, the stop can rest without having a friction drag on the catch even if the bottom section is still rotating due to the passage of fluid by it.

Specifically I have found that following dimensions 50 give good results for a tool adapted to work within a 2 inch I.D. tube. The bodies 12 and 20 are made from $\frac{1}{2}$ inch steel pipe (.840 inch O.D.) each about $8\frac{1}{2}$ inches long. The vanes 16 and 22 each make one complete revolution around the body and are constructed from 12 55 guage steel welded to the body. The entire tool is 20 inches long and weighs three pounds. The diameter of across the vanes is $1\frac{1}{8}$ inches and the diameter of the stop is $1\frac{1}{16}$ inches.

It will be apparent that the embodiment shown is 60 only exemplary and that various modifications can be made in construction, materials, and arrangements within the scope of the invention as defined in the appended claims.

I claim as my invention:

65 1. In a paraffin scraper for an oil well tube including a free member which moves up and down within the tube, the improvement comprising: said member having two portions, an upper tubular portion and a lower tubular portion, each portion having helical vanes on the outside thereof, the outside diameter of said vanes being only slightly less than the inside diameter of said tube, the vanes on the top portion rotating in a first direction

and the vanes on the bottom portion rotating in a second direction, a pintle attached to one of said portions, a washer attached to the other of said portions, said pintle extending through said washer and having a stop at the end of the pintle which is beyond said washer, so that the two members are connected together for relative rotation but with only slight axial movement.

2. The invention as defined in claim 1 with the addition of a disc shaped stop upon the bottom of the bottom portion co-axial therewith, said stop being of lesser diameter than the outside diameter of said vanes but of greater diameter than the diameter of the portion to which the vanes are attached, said stop having a pintle extending upward from the top thereof, said bottom portion having a washer in its bottom, said stop pintle extending through said bottom washer, a protuberance upon the top of the pintle which is above the washer, thus mounting the stop for relative rotation to the bottom portion but little axial movement relative to the bottom portion.

3. A paraffin scraper for oil wells comprising: an upper cylindrical member with helical vanes on the exterior

thereof, said helical vanes rotated around the outside of the member in a first direction; a lower second cylindrical member with helical vanes on the outside thereof, the vanes of the second member rotated around the outside of the second member in a second direction; said cylindrical members being arranged coaxially vertically within a tubular member of said oil well, means connecting said first and second members for free rotation in all positions relative to each other, but for only slight axial movement with respect to each other; and a stop on the bottom of the lower of the two members, said stop having a smooth exterior surface, and said stop being mounted for free rotation relative to the lower of the two members.
